(57) **CLAIM**

The ornamental design for bucket planter divider, as shown and described.

DESCRIPTION

FIG. 1 is a front perspective view of a bucket planter divider, showing my new design, wherein the broken lines show a bucket, wicking cord and plant support rod which form no part of the claimed design;

FIG. 2 is a front perspective view thereof, shown in an alternate position of use;

FIG. 3 is a side plan view thereof, shown at an enlarged scale; FIG. 4 is a top plan view thereof, shown at an enlarged scale; and

FIG. 5 is a bottom plan view thereof, shown at an enlarged scale.

FIG. 6 is a front perspective view of a second embodiment of a bucket planter divider;

FIG. 7 is a side plan view thereof, shown at an enlarged scale; FIG. 8 is a top plan view thereof, shown at an enlarged scale; and

FIG. 9 is a bottom plan view thereof, shown at an enlarged scale.

FIG. 10 is a front perspective view of a third embodiment of a bucket planter divider;

FIG. 11 is a side plan view thereof, shown at an enlarged scale;

FIG. 12 is a top plan view thereof, shown at an enlarged scale; and,

FIG. 13 is a bottom plan view thereof, shown at an enlarged scale.
